UNITED STATES PATENT OFFICE

FRANK E. BLANC, OF KNOXVILLE, TENNESSEE

MOTOR-CAR MEMORANDUM HOLDER

Application filed September 21, 1929. Serial No. 394,257.

The object of this invention is to provide a memorandum holder especially intended for use on motor vehicles and for attachment to a stationary element adjacent to the engine, the device being adapted to carry memoranda regarding the care of the engine, batteries, brakes and lights.

A further object is to provide a holding device in which individual memorandum sheets may be shifted at will, and means for retaining the holder on its support and for retaining the sheets in the holder.

With the foregoing and other objects in view, the invention consists in the novel construction and arrangement of elements disclosed, it being understood that modifications may be made within the scope of the claim without departing from the spirit of the invention.

20 In the drawings forming part of this application:—

Figure 1 is a perspective view showing conventionally the usual elements adjacent to the engine of a motor car, and including 25 the brace rod extending rearwardly from the radiator and above the engine, and selected as the most suitable and convenient mounting device for the memorandum holder.

30 Figure 2 is a face view of the holder with the retaining means in extended position.

Figure 3 is a perspective view showing the holder chiefly from the rear thereof and showing the rod from which it is supported, 35 in dotted lines.

Figures 4 and 5 illustrate a modification in which the retaining means include a bolt or screw and a thumb nut.

In Figure 1 the engine, shown conventionally, is designated 10, the radiator is illustrated at 11, and a brace rod 12 occupies the usual position above the engine, and between the radiator and cowl.

The memorandum holding device includes 45 a plate of sheet metal, such as tin or aluminum, the main portion thereof being designated 14, and said plate having an upward extension 15 provided with transverse slots 16 and 17, or openings of other 50 suitable form.

A tongue 18 is formed on the extension 15, and it will be observed that the complete device is readily made from a single blank sheet. The end portion of the tongue may be tapered as shown at 19, and the strip being of thin material, is readily folded over, so far as the tongue 18 is concerned, so that it may be bent around any supporting element, such as rod 12. Although the device will maintain its position under certain conditions, without displacement, if attached only in the manner just indicated, it is usually desirable to deflect the end portion of the tongue first thru upper slot 16, rearwardly and thence outwardly or forwardly thru slot 17, the forwardly extending portion being bowed outwardly and forming a type of resilient card or sheet holding device, with the extreme end 19' extending inwardly toward the plate 14.

The edge portions of the plate 14 are folded over to form flanges and channel-like portions at the sides, as shown at 20 and 21, and also at the bottom as shown at 22. The sheets or cards are to be inserted 55 between the elements 20, 21 and 22, and a transparent sheet, usually of celluloid will be employed and placed in front of the data sheet or sheets. These sheets will carry any suitable wording as for instance that shown in Figure 2, and relating to the care 60 of the engine, or other portions of the car including the battery, the lights and the brakes.

The sheets to be used may be readily 65 shifted when two or more are employed, and in order to prevent displacement from the holder under any conditions of usual vibration of the vehicle, the outwardly deflected portion of the tongue 18, shown especially 70 at the point 18', serves as a resilient obstruction, readily releasing the cards when desired but preventing displacement accidentally.

In the modification illustrated in Figures 75 4 and 5 the plate member 14 corresponds with that just described, and it is also provided with flanges forming channels along three edge portions.

The extension 15' is provided with an 80

aperture 24, and the tongue 25 is provided with a series of apertures as indicated at 26, and a bolt or screw 27 passing thru aperture 24 and any of the apertures 26, is to be retained by a wing nut 28, providing clamping action between the end portion of the tongue 25 and an adjacent portion thereof, or more particularly the portion 15'.

16. What is claimed is:—

17. A memorandum holder comprising a plate, side flanges formed on the sides and one end of said plate to slidably receive from one end of the plate an indicia bearing card, an extension formed on the last mentioned end of said plate and having spaced slots located adjacent the plate, and a flexible tongue formed on the end of said extension and bent about a support with the end of the extension located adjacent the support, said tongue bent to extend through one slot from one direction and then bent to extend through the adjacent slot from an opposite direction and inclining downwardly and outwardly to overlie a portion of the card to retain said card in the flanges and upon the plate and permit the removal of the card when the free end of said tongue is flexed upwardly from the plate.

25. 30. In testimony whereof I affix my signature.

FRANK E. BLANC.
